CONTAINER FOR HOLDING ODOR ABSORBENT
IN A REFRIGERATOR

Albert Stubbmann, Franklin Lakes, N.J., assignor to Wecolite Company, Inc., Teaneck, N.J.

Filed Sept. 18, 1972, Ser. No. 289,665

Term of patent 3½ years

Int. Cl. D23—04

U.S. Cl. D23—150

FIG. 1

FIG. 2

FIG. 3

FIG. 4

FIG. 5

FIG. 1 is a top plan view of container for holding odor absorbent in a refrigerator showing my new design.

FIGS. 2, 3, 4 and 5 are front, right side, bottom and rear views of said container, respectively.

The left side view is identical to the right side view.

I claim:

The ornamental design for a container for holding odor absorbent in a refrigerator, substantially as shown and described.
